J. E. TESSEYMAN AND T. N. RUSSELL.
CARLINE.

APPLICATION FILED OCT. 23, 1919.

1,428,403.

Patented Sept. 5, 1922.

UNITED STATES PATENT OFFICE.

JOHN E. TESSEYMAN AND THOMAS NATHAN RUSSELL, OF CHICAGO, ILLINOIS,
ASSIGNORS TO CHICAGO-CLEVELAND CAR ROOFING COMPANY, OF CHICAGO,
ILLINOIS, A CORPORATION OF ILLINOIS.

CARLINE.

Application filed October 23, 1919. Serial No. 332,700.

To all whom it may concern:

Be it known that we, JOHN E. TESSEYMAN and THOMAS NATHAN RUSSELL, citizens of the United States, residing in Chicago, in 5 the county of Cook and State of Illinois, have invented a new and useful Improvement in Carlines, of which the following is a specification.

The invention relates to carlines more particularly designed for freight car roofs, and has for its objects to simplify and make more economical the construction of the carline, and at the same time enhance its strength, and resistance against vertical, longitudinal 15 and diagonal strains.

With such objects in view, as well as other advantages which may be incident to the use of the improvements, the invention consists in the parts and combinations thereof 20 hereinafter set forth and claimed, with the understanding that the several necessary elements constituting the same may be varied in proportions and arrangement without departing from the nature and scope of 25 the invention.

In order to make the invention more clearly understood there are shown in the accompanying drawings means for carrying the same into practical effect, without limiting 30 the improvements, in their useful applications, to the particular constructions, which, for the purpose of explanation, have been made the subject of illustration. In the said drawings:

35 Fig. 1 is a plan view of a portion of a car roof frame, comprising a carline embodying the invention.

Fig. 2 is a vertical sectional view of the same including also parts of the car sheathings, this view being taken on a plane transverse of the car.

Fig. 3 is a vertical sectional view on a larger scale taken on the line 3—3 of Fig. 1, the ridge pole being omitted.

45 Referring to the drawings, 1 indicates the ridge pole, 2 the side plates, 4 the purlins, 5 the top sheathing, 6 the side sheathing, and 7 the fascia, of the car frame and body.

Only one of the carlines is illustrated, and 50 it will be understood that a suitable number of said carlines will be supplied in a car frame, to support the ridge pole and purlins, in the manner illustrated. Said carline is

indicated at 8 and is composed of two separate L-shaped bars 9 which are securely 55 united to each other at the ridge pole, inclined gradually away from each other at each side of the ridge pole and to the side plates, and also inclined downwards from the ridge, this last mentioned inclination being 60 according to the desired shape and pitch of the car roof. The horizontal bars of said L-shaped bars are indicated at *a* and the vertical bars at *b*.

At each of the four attachments thus provided for at the side plates the horizontal part of the L-shaped bar extends over and rests on the side plate, this portion of the bar being indicated at 10, and it is secured to the side plate by a vertical bolt 11. The 65 vertical bar of the L-shaped bar is split away from the portion 10, as seen in Fig. 1, so as to provide a longitudinally extending foot 12 which bears against the inner side of the side plate and is secured thereto by one or 70 more bolts 13. The carline thus obtains four very strong attachments to the side frame 75 of the car and each of said attachments has an ample and strong bearing, both downward on the side plate and outward against its inner surface.

At the ridge of the car the horizontal members of the L-shaped bars are lapped one over the other (Fig. 3) one of said members being preferably depressed to form a seat 14. 80 The carline thus obtains four very strong attachments to the side frame of the car and each of said attachments has an ample and strong bearing, both downward on the side plate and outward against its inner surface.

At each end of the said lapped portions of carline bars, the bars are so bent as to incline away from each other (Fig. 1) and at or near these points of divergence the vertical members of the bars are united together by longitudinal rivets or bolts 16 (Fig. 3), which act as strong ties to counteract any 95 tendency of the vertical bar members to be spread apart by the super-posed weight of the car roof.

The purlins 4 rest on and are suitably united with the horizontal members of the 100 bars by bolts 17 (Fig. 1). The ridge pole 1 is similarly united with the carline by a bolt 18.

It will be understood that the depression or formation which produces the seat 14 105 may or does extend as far as one of the car-

line bars laps over the other, the same being indicated by dotted lines in Fig. 2.

The seat 14 has two distinct functions, one of which is to bring the top surfaces of the two carline bars flush with each other in the same horizontal plane, but an important function of the same is to provide the wall 21 which opposes and receives the pressure of the edge of the contained horizontal web *a*, thereby taking the shearing strain off of the rivets 15 when the weight of the roof presses the upper members of the carline bars strongly towards each other. Such compression together of the two carline members at the shoulder or wall 21 normally produces twisting strains in each of said members, but these twisting strains are entirely counteracted by the tie members 16, so that the carline structure at the apex is perfectly balanced for the resistance of strains and for durability.

It will be seen that by the above structure, bars of L formation are so utilized as to provide a wide central portion at the apex of the carline which is very strong to resist the weight of the roof, and other strains which come to bear upon said apex.

At the outer ends of the carline members the downward inclination thereof may terminate at the point indicated at 19 in Fig. 2, and said members may extend thence horizontally, as shown in Fig. 2, for the described engagement with the side plates.

What is claimed is:

35 1. In a carline for car roofs and the like, the combination of two L-shaped bars each of which is adapted to extend from side to side of the roof, said bars having their horizontal members lapped one on the other at the ridge, one of said bars being formed with a shoulder against which abuts the edge of the horizontal member of the other bar, said bars thence inclining away from each other, and declining towards their outer ends, and means whereby said lapped members are secured together.

50 2. In a carline for car roofs and the like, the combination of two L-shaped bars each of which is adapted to extend from side to side of the roof, said bars having their horizontal members lapped one on the other at the ridge, one of said bars being formed with a shoulder against which abuts the edge of the horizontal member of the other bar, said bars thence inclining away from each other, and declining towards their outer

ends, means whereby said lapped members are secured together, and a tie member connecting the vertical members of the bars together below their lapped parts.

60 3. In a carline for car roofs and the like, the combination of two L-shaped bars each of which is adapted to extend from side to side of the roof, said bars having their horizontal members lapped one on the other at the ridge, said bars thence inclining away from each other, and declining towards their outer ends, means whereby said lapped members are secured together, and a tie member connecting the vertical members of the bars together below their lapped parts.

70 4. In a carline for car roofs and the like, the combination of two L-shaped bars each of which is adapted to extend from side to side of the roof, said bars having their horizontal members extending towards each other and arranged to abut each other and secured one to the other and having their vertical members spaced apart, and a tie member securing their vertical members one to the other, said bars inclining away from each other and also declining towards their outer ends.

75 5. In a carline construction for car roofs and the like, in combination: a pair of carline members respectively extended from side to side of a roof and respectively provided at the ridge with horizontal portions lapped one on the other, the horizontal portion of one carline member being provided with a shoulder against which abuts the horizontal portion of the other carline member; and securing means passed through said lapped horizontal portions for uniting the carline members at the ridge.

80 6. In a carline construction for car roofs and the like, in combination: a pair of carline members one lapping the other at the ridge of the roof, and securing means passed through the lapped portions of the carline members for uniting them at the ridge, the lapped portion of one carline member being provided with a shoulder against which abuts the lapped portion of the other carline member to limit the relative movement of said lapped portions and to prevent shearing of said securing means.

85 In testimony whereof we have hereunto set our hands.

JOHN E. TESSEYMAN.
THOMAS NATHAN RUSSELL.
